UNITED STATES PATENT OFFICE

JOHN A. HARRIS, OF DETROIT, MICHIGAN

STEAM MOTOR VEHICLE

Application filed February 11, 1927. Serial No. 167,390.

This invention relates to motor vehicles, and relates particularly to steam propelled vehicles.

An object of the invention is to provide a boiler for the power plant of a steam propelled vehicle (or for a stationary power plant) employing a detachable base within which the combustion gases from a burner are adapted to circulate, said base providing a large surface area for the transfer of heat from said gases to water in the boiler, whereby an instantaneous or flash generation of steam may be continuously effected.

Another object is to provide a novel automatic regulator for the water-level in a boiler.

These and various other objects the invention attains by the construction herein-after described and illustrated in the accompanying drawings, wherein,

Figure 1 is a plan view of a chassis of a motor vehicle diagrammatically showing a power plant embodying the improved construction.

Figure 2 is a view of the same in sectional elevation taken on line 2-2 of Figure 1.

Figure 3 is a vertical sectional view of the boiler particularly showing the detachable heat transferring base.

Figure 4 is a view similar to Figure 3 illustrating an alternative construction of the detachable boiler base.

Figure 5 is a horizontal sectional view of said alternative construction, taken on line 5-5 of Figure 4.

In these views the reference character 1 designates a rear axle, which may be of standard construction, comprising the usual live axle sections 2, adapted to be driven through a differential gearing 3.

A steam engine 4 of any suitable construction furnishes motive power for the vehicle, the crank shaft 5 of said engine being illustrated as driving the differential 3 through a suitable gearing 6.

The engine 4 derives steam from a boiler 7 mounted preferably upon the front portion of the vehicle, 8 designating a steam delivery pipe leading to said engine from the top portion of the boiler. The steam exhaust-

ing from the engine is carried through a pipe 9 having a condenser portion 10 arranged within and discharging in the lower portion of the tank 11 which stores feed water for the boiler. From said tank the water is delivered by a pipe 12 to a suitable pump 13 adapted to deliver such water through a pipe 13a against the steam pressure of the boiler.

The boiler is adapted to be heated by a suitable burner 15 to which liquid fuel may be delivered through a pipe 16 from a suitable fuel reservoir 17.

It is preferred to maintain a pressure upon the fuel in the reservoir 17 to assist the flow of fuel therefrom to the burner and for this purpose an air connection 18 is established to the top of said fuel tank, from a suitable compressor 19 driven by the engine.

The base of the boiler is detachably secured to the body thereof by bolts 20a, or the like, and said base is formed with a plurality of substantially circular passages 21 through which combustion gases from the burner 15 are adapted to circulate. By this construction, there is provided a large heat transfer surface over which the feed water may be spread by a suitable perforated discharge head 21a upon the feed pipe 13a, so that the water will be quickly flashed into steam and will rapidly build up a steam pressure.

In the alternative construction shown in Figures 4 and 5 the hollow base is formed with a plurality of upstanding cylindrical projections 22, which provide the desired large area for transfer of heat. Preferably the tops of said projections are dished to form shallow water containers.

As a provision for avoiding any accumulation of water in the boiler 7, a by-pass pipe 23 is arranged to connect the lower portions of the boiler and the water tank 11, said pipe being controlled within the boiler by a normally closed valve 24 which is under control of a float 25 mounted upon an arm 26. It is preferred to provide a check valve 26a in the pipe 23, preventing any back flow from the water tank to the boiler when there is no steam pressure in the latter.

If the water accumulates to a slight extent in the bottom portion of the boiler the float 25 rises and opens the valve 24, whereupon the steam pressure in the boiler immediately 5 forces such water through the by-pass pipe 23.

An overflow pipe 27 opening in the top portion of the water tank passes through the bottom of said tank and after extending rearwardly through the burner chamber 28 opens 10 to the atmosphere. Said pipe serves also to exhaust any steam that may collect in the top portion of said tank. In the event that the water supply to the feed pump 13 is reduced below normal, by a valve 29 in the 15 pipe 12 or by some other suitable regulating means, air may be drawn through the pipe 27 into the water tank, preheated by its passage through the chamber 28, and may be delivered to the pump 13 through a pipe 30 20 leading therefrom to the top portion of the water tank. When heated air is so delivered it will supplement the steam in the boiler and thus economize on fuel.

It will be noted that the delivery of exhaust 25 steam into the feed water tank 11 through the condenser 10 in said tank serves both to condense such steam and to preheat the water in said tank.

Among the advantages of the described 30 construction are the use of a standard rear axle, a large heat transfer area, provided by the detachable base of the boiler, the provision for ready repair of the boiler base resulting from its detachability, and an accurate prevention of flooding of the boiler or 35 of any undue accumulation of water therein.

What I claim is:—

The combination with a boiler having an upwardly concaved boiler base, and having a 40 plurality of tubular projections integral with and upstanding from said base, open at their lower ends and having closed upper ends formed with shallow depressions in their top faces, means within said boiler for discharging 45 water downwardly upon said projections, and means below said boiler for discharging heated gases into said tubular projections.

In testimony whereof I sign this specification.

50

JOHN A. HARRIS.
